UNITED STATES PATENT OFFICE

CHARLES H. APPS, OF EAST ORANGE, NEW JERSEY

LOCOMOTIVE

Original application filed November 29, 1929, Serial No. 410,346, Patent No. 1,871,295, dated August 9, 1932.
 Divided and this application filed December 17, 1931. Serial No. 581,580.

This invention relates to locomotives, and more particularly to cylinder saddles, valve chests, and cylinders associated with main locomotive frames.

5 An object of the present invention is to provide a locomotive structure of greater strength, and which can be more economically manufactured and maintained than those heretofore known.

10 A further object of the invention is to provide a fabricated locomotive structure which, while possessing the advantage that its parts may be separately formed, will have substantially the strength, rigidity, and durability 15 of an integrally cast structure.

A further object of the invention is to provide a structure wherein there is combined a locomotive frame, and a cylinder saddle and bumper beam bracket, which structure is 20 more economical to manufacture and maintain, and possesses greater strength than those heretofore known.

A further object of the invention is to provide a cylinder saddle and cylinder castings 25 so formed that when assembled they will present a flat platform for the application of a flat bottom of a smoke box, thus obviating the expensive machining operations required to provide such parts with a curved fit for a 30 cylindrical smoke box.

A further object of the invention is to combine, in an integral casting, a cylinder saddle, a bumper beam bracket, guide yoke supports, a cross tie for the supports, brake 35 cylinder supports, brake lever fulcrums, and a truck center pin.

A further object of the invention is to combine with the novel frame and cylinder saddle construction, separately formed castings, each embodying a cylinder and a distribution valve chest, thus effecting a substantial economy in manufacturing cost, lessening the danger of shrink cracks, and providing a structure, the parts of which can be 45 readily disassembled for repairs.

A further object of the invention is to provide a novel construction of smoke box and cylinder castings, wherein the steam supply passage to the distribution valve 50 chest leads through the cylinder castings di-

rectly into the smoke box without passing outside of the casting or the smoke box, as in former practice.

Other objects and advantages of the present invention will appear from the following detailed description and appended claims.

The invention is illustrated in the accompanying drawings, in which Fig. 1 is a fragmental plan view of a structure for locomotives embodying the present invention; Fig. 2 is a fragmental side elevation of the structure shown in Fig. 1, with a smoke box applied thereto; Fig. 3 is a view of the structure shown in Fig. 1, the right half being in front elevation, and the left half being in transverse vertical section, on the line III—III of Fig. 1; Fig. 4 is a view, on an enlarged scale, of the cylinder saddle casting, the right half being in front elevation, and the left half being in transverse vertical section, on the line IV—IV of Fig. 6; Fig. 5 is an enlarged view of the cylinder saddle casting, the upper half being in plan, and the lower half being a longitudinal horizontal section, on the line V—V of Fig. 6; and Fig. 6 is a longitudinal vertical sectional view of the cylinder saddle casting taken on the line VI—VI of Fig. 5.

In the practice of the invention, referring descriptively to an approved embodiment thereof which has been selected for exemplification herein, the main frame comprises two side members 1, embodying pedestal jaws 2, of conventional design, each of the side members employing top rails 3, and bottom rails 4. The side members are joined together at their tops by a top horizontal plate 5, which may be of rolled steel or other suitable material, and which is welded to the top rails 3. The bottom rails 4 are joined together by bottom horizontal plates 6, of similar material to the plate 5, and are similarly welded in position.

The present invention is a division of my prior parent application Serial No. 410,346, filed November 29, 1929, now Patent No. 1,871,295, of August 9, 1932, and it will be understood that the main frame structure

contemplated for use with the embodiments of the present invention herein exemplified, may be the same as that described as the approved embodiment of the invention in the aforesaid parent application.

The combined cylinder saddle and bumper beam bracket structure, comprises, in an integral casting, a saddle 10, a bumper bracket 11, a truck center pin 12, guide yoke supports 13, a cross tie 14, for the guide yoke supports, brake cylinder supports 15, and brake lever fulcrums 17.

The saddle 10 is substantially box shaped, comprising vertical side walls 18, vertical end walls 19, a flat horizontal bottom wall 20, and a flat horizontal top wall 21. Leading through the saddle from each of the side walls 18 to the top wall 21, are exhaust steam passages 22. The side walls 18 of the saddle are extended beyond the end walls 19 to provide flanges 23, having bolt holes 24, for attachment of the side frame members 1, and cylinder castings to the cylinder saddle. The top wall 21 of the saddle is extended beyond the end walls 19 to provide flanges 25, having bolt holes 26 for the attachment of a flat plate 27 of smoke box 28.

The truck center pin 12 projects vertically downward from the horizontal bottom wall 20 of the saddle.

The bumper beam bracket 11 is connected to the front end wall 19 of the saddle by a horizontal web 29, and longitudinal vertical flanges 30, joining the side walls 18, and having bolt holes 31, for bolting the side frame members 1 to the saddle. It will be understood that a bumper beam (not shown) may be either detachably bolted to the bracket 11 or integrally formed therewith.

Extending to the rear of the cylinder saddle is a box shaped structure 32, comprising vertical side walls 33, joined to and in alignment with the side walls 18, and their rear flanges 23, and having bolt holes 34, for bolting the side frame members 1 to the casting. The aforesaid brake cylinder supports 15, for the attachment of the usual brake cylinders (not shown) are formed on the walls 33. The rear structure 32, also comprises a bottom wall 35 joined to and in alignment with the wall 20; longitudinal reinforcing ribs 36; and a rear wall 37, which extends vertically above, and laterally beyond, the side walls 33, to provide, at its opposite ends, the aforesaid guide yoke supports 13, and a cross tie 14 therefor. The wall 14 provides a support to which a bracket of any well known design may be secured and extended upwardly for supporting the waist of the locomotive boiler to the rear of the smoke box.

Extending to the rear of the box shaped structure 32, are vertical flanges 38, formed

with the aforementioned brake lever fulcrums 17, and bolt holes 39, for attachment of the casting to the side frame members 1. Extending rearwardly of the rear wall 37, is a horizontal flange 40, to which the top plate 5, of the frame, is connected by welding (not shown). Vertical reinforcing ribs 41, 42 and 43, similar to ribs 36, are provided between the walls 18 and 19 and the bracket 11.

Each cylinder casting 50 comprises a cylinder 51; a distribution valve chest 52; a flat top wall 53, having end flanges 54, and a side flange 55, the said flanges having bolt holes 56, formed therein, for attachment of the flat bottom plate 27 of the smoke box 28, and the flanges 54, matching with the flanges 25 of the saddle. An inlet passageway 57, leading from an adjacent opening 58, formed in the bottom of the smoke box, for supplying steam to the valve chest, and an outlet exhaust passageway 59, leading from the valve chest to the adjacent cylinder saddle passageway 22, are formed in the cylinder casting. By referring to Fig. 3 of the drawings, it will be seen that the steam supply passageway 57, leading through the cylinder casting from the valve chest to the opening 58, located inwardly of the side of the smoke box, thus avoids the use of steam supply pipes outside of the smoke box and valve chest, as in former practice.

The vertical flanges 30 are offset at their forward ends providing laterally extending shoulders 30a against which the front ends of the side frame members 1 abut. The cylinder castings 50 are formed with inner walls 60, the upper parts of which walls bear against the side walls 18 of the cylinder saddle and their flanges 23, and the lower parts of which are offset to provide spaces adjacent the walls 18, through which spaces the side frame members 1 extend. Bolts 61 are passed through the walls 60 of the cylinder castings, and the flanges 23 of the cylinder saddle respectively, and through the side frame members, securing the parts together. The lower edges of the forward ends of the side frame members 1 are provided with lateral flanges 1a which extend along the lower edges of the walls 60 and the walls 18 and their flanges 23, thereby making for a more secure jointure of the parts.

The aforescribed invention possesses the following advantages:
It provides a construction comprising various associated locomotive parts formed as a casting and adapted to withstand the heavy stresses incident to service. It provides a cylinder saddle and cylinder casting construction embodying a flat top wall that may be used with a flat bottomed smoke box, the assembly being more economical to manufacture and maintain, than the constructions heretofore known. It provides for steam

supply to the valve chest by passages leading through the cylinder casting directly into the smoke box, thus obviating the outside steam supply pipes, and their lagging, as required in former practice.

While there has been hereinbefore described a preferred embodiment of the present invention, it will be understood that many and various changes and modifications 10 in procedure, form, arrangement and construction of parts, may be made thereto without departing from the spirit of the instant invention, and that all and any such changes and modifications as fall within the scope of 15 the appended claims are contemplated as a part of the instant invention.

The invention claimed and desired to be secured by Letters Patent is:

1. A structure for use in locomotives, comprising a pair of side frame members; a cylinder saddle disposed therebetween and having a flat top for directly partially supporting a smoke box; and a cylinder casting secured to the saddle and having a flat top 25 for partially supporting said smoke box.

2. A casting for locomotives, comprising a cylinder, a distribution valve chest, and a flat top disposed above the distribution valve chest adapted to support a portion of a 30 smoke box.

3. A casting for locomotives, comprising a cylinder, a distribution valve chest, a flat top disposed above the distribution valve chest adapted to support a portion of a 35 smoke box, and a steam passageway leading from the flat top to the distribution valve chest.

4. A structure for use in locomotives, comprising a pair of side frame members; a 40 cylinder saddle casting disposed between said members and secured thereto, said casting having a flat top for partially supporting a smoke box, and comprising guide yoke supports, a cross-tie for said supports, brake lever fulcrums, and a bumper beam bracket; and a cylinder casting secured to said cylinder saddle casting and having a flat top for 45 partially supporting a smoke box.

5. A separate casting for locomotives, comprising a cylinder, a distribution valve chest, a flat portion adapted to support a portion of a smoke box, and means adapted for connection with a separate cylinder saddle.

CHARLES H. APPS.
